UNITED STATES PATENT OFFICE.

JOHN HASSELBRING, OF NEW YORK, N. Y.

DESIGN FOR A BOTTLE-OPENER.

No. 38,166.

Specification for Design.

Patented Aug. 14, 1906.

Application filed March 21, 1906. Serial No. 307,285. Term of patent 7 years.

To all whom it may concern:

Be it known that I, JOHN HASSELBRING, a citizen of the United States, residing in New York, in the borough of Brooklyn, county of Kings, and State of New York, have invented a new, original, and ornamental Design for Bottle-Openers, of which the following is a specification, reference being had to the accompanying drawings, forming part thereof, and in which—

Figure 1 represents a plan view; and Fig. 2

is a vertical longitudinal section on line 2 2, Fig. 1, of a bottle-opener, showing my new design.

I claim—

The ornamental design for a bottle-opener, as herein shown.

JOHN HASSELBRING.
